HOUSEHOLD IMPLEMENT

Karl Richter, Elkins Park, Pa.

Application February 16, 1937, Serial No. 125,959

2 Claims. (Cl. 81—3.1)

My combined household implement combines means for opening or closing screw top jars, can opening devices of two kinds, a cork screw and a cap remover for bottles. Several of these devices may be used separately, especially that for opening or closing caps of screw top jars. The means by which all these devices are combined into a single implement are also features of my invention, as are also the means by which several are combined with the handle, especially the jar opener and closer, and the can openers and bottle stopper. The jar opener alone, has also particular advantages. It gives a very strong leverage and grips tightly the cap of the jar in such a way that it is not deformed. This is important for the housewife who puts up her canning in glass jars having a metal cap that screws down on a rubber or other compressible gasket positioned between the bottom of the cap and a shoulder on the jar, to seal the jar. A woman's hand is often too weak to turn the cap sufficiently forcibly, and any deformation of the cap will cause it to fit imperfectly and admit air. Besides, the cap can be taken off by my device without deformation, and can be re-used indefinitely. This facility helps the woman who preserves for her own family's use, for she re-uses her jars repeatedly.

Describing now my device:

Fig. 1 is a top plan view of my device. Fig. 2 is a section on line 2—2 of Fig. 1, in position for use in unscrewing the cap of a jar. Fig. 3 is a view of the bottom of the device.

The device has a handle 7 that serves for each of the instrumentalities, and has the rib 10 that strengthens it, preferably at right angles to its main portion placed at the side. This may be struck out from a blank. In the main body of the handle 7 is a bottle cap remover 9 which I usually form with a straight edge b opposite a curved edge c and place at the opposite end of the handle from the can opening instrumentalities. The can opening devices 4 and 8 are placed at the opposite end of the handle from the bottle opener and may be of any form of can opening devices, either cutting or prying. The instrumentality 4 is shown as the ordinary cutting knife formed out of the end of the main body of the handle, and the instrumentality 8 may be formed from the extremity of the rib. These instrumentalities are well known, and the novelty of my device in respect to them lies in the extremely efficient way they are combined with the handle 7. A cork screw 12 may be added to this handle. It is nested in the handle and the

slot 19 permits it to be extended on either side of the main part of the handle 7. The rib 10 projects above it and when the implement rests either side uppermost, prevents it from catching in a table cloth or similar article. The cork screw 12 is carried by the shaft 13, which is journaled at one end of the rib 10. The inclusion of the cork screw makes a very complete household instrument, and the way it is mounted is novel, but, as comparatively few bottles are now cork sealed, and it adds substantially to the manufacturing costs, it may be omitted, where cheapness is a requisite.

The element of the cap remover and cap placed is novel in its construction and exceedingly efficient in operation. Its chief part is a strap of flexible material of sufficient strength 5, which is adapted to encompass the sides of the cap 21, in a way that makes it slightly slidable around it until the strap is clamped tightly around it when it grips unslidably the cap 21, but in such a way that nothing but the leather contacts the cap. The portion of the handle shown to the right of the strap in the drawing, does not contact with the gripping loop 27 of the strap 5 the latter being drawn tight enough around the cap, to cause the latter to turn before any part of the handle can touch the loop 27. One end 17 of this strap 5, is firmly fastened to the handle 7, preferably at the lower side of the main portion of the handle and by the fasteners 14, (screws, rivets or other fastening devices of suitable character). It is slotted, if necessary, to prevent it from interfering with the movement of the cork screw 12. The strap 5 is acted upon by an abutment, preferably the transverse edge 16 of a narrow slot 22 in the handle of the implement and has a loop 27 adapted to encompass the cap 21 and the free end 6 of the strap contacts with the jaw 15, which, in conjunction with the abutment 16, tightens the loop 27 on the cap, until the cap is firmly gripped by it, when the handle 7 is turned. The lip or jaw 15 is inclined at an acute angle with the handle towards that part thereof that is shown in the drawing as lying to the left of the slot. It is close enough to the transverse edge of this slot and long enough to engage the portion of the free end of the strap adjacent to the slot on the side thereof toward the loop 27 where it lies in close contact with the portion of the fixed end of the strap lying in the slot. When the handle is turned it is in position to press the two thicknesses of the strap closely together drawing down the free portion of the strap and clamping 55

the loop 27 tightly around the cap and press the two portions of strapping down hard on each other. When turning the handle to loosen the cap, the lip or jaw 15 will be withdrawn 5 toward the handle still more, and further away from the loop 27, and the abutment formed by the edge of the slot also pulled away from the loop 27, the frictional hold of the loop around the cap and the pull upon this loop on the strap 10 exerted by the abutment 16 being the sole means of loosening and removing the cap. No portion of the handle comes into contact with the loop 27 or with the cap itself. If the device is skillfully made and operated with reasonable care, 15 the jaw 15 will contract the loop 27 as (looking at Fig. 2) the handle is pulled, by pulling on the bite of the strap 5 and pulling it down and very tight around the cap 21, and the handle itself will never come into contact with the cap 20 or with the loop. The jaw 15 may be provided by striking up a lip out of the material of the handle, and the striking up of this lip will form a slot, as above set forth, for the passage of the strap. The implement, as shown in Fig. 2, is in 25 position to open the cap, the jar being supposed to lie away from the observer. By reversing the position of the jar or of the opener, the cap may be closed down much more firmly than by hand, and without any danger of deforming the cap. The strap 5 may have the loop 27 put 30 around the cap and the end 6 of the strap drawn down firmly while the loop and cap occupy the position shown in Fig. 2, or the cap and loop may be positioned a little to the left of their 35 position in that figure. The turning of the handle around the abutment 16 will cause the jaw 15 to press down the part of the strap in contact

with it, causing the clamping of the loop 27 around cap 21 which will cause the loop to become so tight that, if properly handled, the cap may be unscrewed without bringing the handle into any contact with the cap 21. 5

While I have described very minutely and with great detail the construction of my implement, I do not wish these details to be thought by the reader of this to be limitations on my invention, and do declare that my invention is not limited to anything less than the structure defined by the claims attached to this specification. 10

I claim:

1. An opener for removing the caps from preserving jars, comprising a flat handle having a 15 slot intermediate between the ends of said handle, said slot having a transverse edge, a strap fastened fixedly at one end to the handle and passing through said slot and forming a loop encompassing said cap, and having a free end 20 also passing through said slot, but in the opposite direction, a lip positioned at said slot opposite said transverse edge and forming part of said handle and set at an acute angle with said handle and inclined towards said transverse edge 25 of said slot; the inclined lip and the transverse edge of said slot being positioned closely enough together to hold the two portions of said strap passing through said slot, closely against each other, the said lip bearing solely on the portion 30 of the free end of the strap passing through the slot, and being free from all portions of said loop.

2. The device described in claim 1, wherein the inclined lip is struck up from the material of 35 the handle.

KARL RICHTER.
